UNITED STATES PATENT OFFICE.

WILLIAM F. DONATHAN, OF MEMPHIS, TENNESSEE, ASSIGNOR TO STEPHEN J. GRAHAM, OF TUCKERMAN, ARKANSAS.

COIN-CONTROLLED VENDING MACHINE.

Application filed November 30, 1925. Serial No. 72,375.

This invention relates to improvements in coin controlled vending machines, and has for its principal object to provide a highly novel, yet simple means for dispensing merchandise which is preferably put up in package form.

One of the important objects of the present invention is to provide a vending machine of the above mentioned character which includes a means for effecting the actuation of the package ejector mechanism when the proper coin or coins are inserted in the machine.

Another salient object is to provide a coin controlled vending machine which includes a means for making change when a coin of a higher denomination is inserted in the machine, the difference in the value of the two coins being returned to the purchaser of the merchandise simultaneous with the delivery of the article vended.

Another important object is to provide a coin controlled vending machine which includes a series of change receiving magazines, the same being automatically filled by the coins which are inserted in the machine by the purchasers of the merchandise vended, thus obviating the necessity of having to refill the change holding magazines as must now be done with coin controlled vending machines embodying a change making apparatus.

A still further object is to provide a coin controlled vending machine of the above mentioned character which is simple in construction, inexpensive, strong and durable and furthermore adapted for the purposes for which it is designed.

Other objects and advantages of this invention will become apparent during the course of the following description.

In the accompanying drawings forming a part of the specification and in which like numerals designate like parts throughout the

Figure 1 is a vertical sectional view taken through the coin controlled vending machine.

Figure 2 is a similar section taken at right angles thereto.

Figure 3 is a horizontal sectional view taken approximately on line 3-3 of Figure 2, the lower portion of the slug chute being omitted.

Figure 4 is a similar section taken approximately on line 4-4 of Figure 1 looking in the direction of the arrows.

Figure 5 is a horizontal section taken approximately on line 5-5 of Figure 2 looking in the direction of the arrows.

Figure 6 is a side elevation of one pair of spaced complementary discs; one of said discs being partly broken away.

Figures 7 and 8 are details of the discs showing the arrangement of the curved ribs on the inner opposed faces thereof.

Figure 9 is a transverse section taken approximately on line 9-9 of Figure 1 showing the coin control mechanism in top plan.

Figure 10 is a detail perspective view of the ejector block and its support.

Figure 11 is a detail perspective view of one of the coin receiving plates and the ejector actuating pins associated therewith.

Figure 12 is a similar view of another of said plates.

Figure 13 is a diagrammatic view of the initial coin receiving mechanism showing a slug which has been inserted in the machine.

Figure 14 is a detail perspective view of the deflector plate forming a part of the initial coin receiving mechanism, and

Figure 15 is an enlarged fragmentary detail of one of the grooved rollers showing the same positioned in one of the notches provided in the upper edge of the annular track.

In the drawings wherein for the purpose of illustration is shown the preferred embodiment of my invention, the numeral 1 designates the base, and extending upwardly therefrom is the circular track 2. A series of notches 3 are formed in the upper edge of the track and are arranged at spaced intervals in a manner as is more clearly illustrated in Figure 3. The purpose of the track and the notches will be hereinafter more fully described.

Adapted for rotation on the base is the casing 4. Arranged on the inner side of the casing are a series of vertically disposed compartments or magazines, which are denoted by the numeral 5. These compartments or magazines extend from the top of the casing to the bottom thereof.

Each side or face of the casing 4 is provided with the enlarged cut out portion 7, and a glass panel 8 is disposed over each

cut out portion on the inside of the casing 4, suitable guides 9 being provided for receiving and supporting the glass panels in position over the open front side of the respective compartments or magazines 5. This construction enables the merchandise to be displayed so that a prospective purchaser may rotate the casing until the article which is to be purchased is disposed in vertical alignment with the delivery chute 10, the latter extending laterally from the base and the circular track 1 and 2 respectively. The construction of the base and casing is more fully illustrated and described in a divisional application covering the vending machine cabinet construction per se. The merchandise is preferably put up in package form, and by providing a number of magazines or compartments, various articles may be dispensed from the machine, such as chewing gum, cigarettes, cigars, candy, and the like.

A series of grooved rollers 13 are journaled in suitable openings 14 provided in the annular flange 12 at spaced intervals, the grooved rollers being adapted to travel on the upper edge of the track 2, and being further adapted to cooperate with the spaced notches 3. This is more clearly illustrated in Figure 15 of the drawings. The housing 15 is provided for each of the rollers, and associated with each housing is a suitable handle or gripping member 16 whereby a person may grasp any of the handles, and thus rotate the polygonal shaped casing 4 on the track 2. The grooved rollers 13 are so arranged as to be disposed within the notches 3 so that the casing will be prevented from further rotation of its own accord. In order that the casing may be rotated on the track, it is necessary that the grooved rollers be disengaged from the notches, and this is accomplished by grasping and actuating any of the handles 16.

The magazines or compartments 5 are filled with packages to be vended from the top of the casing, and a suitable cover such as is shown at 17 is removably secured on the top of the casing 4. The upper central portion of the cover is open as indicated at 18 and the purpose thereof will hereinafter be more fully described.

Arranged within the rotatable casing 4 is the stationary cylindrical casing 19. This stationary cylindrical casing is fixed to the floor or bottom 20, the latter being arranged within the base 1, and being further associated with the lower portion of the circular track 2. The stationary cylindrical casing 19 extends upwardly through the bottom 6 of the rotatable casing 4, and as is clearly illustrated in Figure 2 of the drawings, the article receiving magazines or compartments 5 have their rear or inner walls engaging the outer wall of the inner casing.

However, the stationary casing will not interfere with the rotation of the outer casing 4, and the magazines carried thereby.

The stationary cylindrical casing 19 is also provided with a suitable cut out portion 21 adjacent the bottom thereof, and these cut out portions register with similar shaped cut out portions 22 formed in the bottom of the rear or inner wall of each of the article receiving magazines or compartments 5, as is clearly illustrated in Figure 1.

A cover 23 is disposed over the opening 18 formed in the central portion of the cover 17 which is provided for the top of the casing, and this cover 23 is supported in a stationary manner by means of the bracket 24. The lower ends of these brackets are secured to the inner wall of the stationary cylindrical casing 19, in the manner as clearly illustrated in Figure 1. The central portion of the cover 23 is thickened, and arranged therein are the vertical coin receiving slots 25, 26, and 27 respectively. The slot 25 is of such size as to be adapted to receive a five-cent piece, the slot 26 is adapted to receive a ten cent piece, and the slot 27 is adapted to receive a twenty-five cent piece. Suitable indicating means such as is shown at 28 is associated with each of the slots.

The construction of the initial coin receiving means as well as the fraud preventing device included therein is fully covered in a divisional application on the fraud preventing device per se, but, for the purpose of showing the manner in which said aforementioned means is associated with the secondary coin receiving means or coin control mechanism, a brief description thereof follows herewith.

Carried by the bottom of the cover 23, and extending downwardly into the upper portion of the stationary cylindrical casing 19 are the coin chutes 29, 30, and 31 respectively. The upper ends of these coin chutes register with the bottom of the respective coin receiving slots, and these chutes are also of such width as to receive coins of a predetermined denomination.

A transversely extending relatively thick shaft 32 is journaled at its respective ends 115 in the frame 33 and is adapted for rotation therein, this shaft being disposed directly below the lower ends of the respective coin chutes and depending from the bottom of the cover 23. The frame 33 is supported on the 120 brackets 33' which extend upwardly from a pair of block sections hereinafter more fully described. The shaft 32 has formed therein at predetermined places, a series of 125 coin receiving pockets such as is shown at 35. These pockets cooperate with the lower ends of the coin chutes 29, 30 and 31 respectively in the manner to be presently apparent.

A series of spaced knurled rollers 37 are mounted on the frame adjacent the shaft 130

32 in spaced relation thereto and directly opposite the several coin receiving pockets which are formed in the shaft. As is shown more clearly in Figures 1 and 13 respectively, each roller is journaled for rotation in the upper portion of the suitable bracket 38, the lower end of each bracket being pivotally supported at 39 in the frame. This will permit the swinging movement of 10 each roller toward and away from the shaft 32. A curved flat spring 40 is secured in its lower end on the frame directly behind each bracket 38, the upper free end of each spring being in engagement with the upper 15 rear portion of the respective brackets for normally forcing the knurled rollers toward the shaft 32. The set screws 41 which are threaded transversely through the support 42 therefor at the rear longitudinal side of 20 the frame 33 engage the respective spring elements for adjusting the tension thereof.

A substantially rectangular plate 43 is rigidly secured in a longitudinal cut out portion provided therefor in the shaft 44 and 25 the latter is provided with suitable trunnions 45 at its respective ends. These trunnions are journaled in the respective ends of the frame 33 so that the rotatable shaft 44 is disposed longitudinally in the frame 30 and below the aforementioned shaft 32 and slightly rearwardly thereof as shown more clearly in Figure 1.

The shafts 32 and 44 are adapted for simultaneous rotation through the medium 35 of the intermeshing gears 46 and 47 respectively. An elongated hopper 48 is arranged below the shaft 44, and the rear side thereof is cut away as illustrated in Figures 1 and 13 respectively of the drawings for cooperation 40 with the plate 43 which is secured on the shaft 44. Extending downwardly from the bottom of the hopper and communicating therewith are the additional coin chutes 49, 50, and 51 respectively, the same 45 being preferably arranged in alignment with the coin receiving pockets formed in the rotatable shaft 32. As is more clearly illustrated in Figure 2, the last mentioned coin chutes are disposed directly below the 50 coin chutes 29, 30 and 31 respectively. The lower ends of the coin chutes 49, 50 and 51 are slightly cut away to accommodate the various coin receiving discs, the construction of which will be presently described.

55 The specific means for effecting the rotation of the shafts 32 and 44 so as to position the plate 43 with respect to the hopper 48 will also be hereinafter more fully described, and is also fully set forth in the aforementioned divisional application.

The specific construction of the secondary coin receiving means, or coin control mechanism which is embodied in the present application will now be described, and attention

is particularly directed to Figures 1, 2, 65 and 9 of the drawings.

Extending transversely in the upper portion of the stationary cylindrical casing 19 below the frame 33 and secured to the inner walls of the casing in any suitable manner, 70 are the block sections 52 and 53. The inner opposed faces of these block sections are cut away as indicated at 54 with reference more particularly to Figure 9. The blocks 52 and 53 are further provided with the longitudinally extending vertically cut out portions 55 and 56 respectively. The purpose of this construction will be presently apparent. Lateral extensions 57 and 58 are 75 formed on the lower portions of the blocks 80 52 and 53 respectively.

A pair of transversely extending aligned shafts 59 and 60 which extend through the blocks 52 and 53 respectively, adjacent one end thereof, a similar pair of aligned shafts 85 are journaled transversely in the other end portion of the block, and these shafts are designated by the numerals 61 and 62 respectively. An additional pair of aligned shafts 63 and 64 respectively are journaled transversely in the blocks 52 and 53 and are further disposed intermediate the aforementioned pairs of aligned shafts as is clearly 90 illustrated in Figure 9 of the drawing.

The inner opposed ends of these pairs of shafts extend into the intermediate cut away portion 54. The cut away portion 55 formed in the block 52 provides a means whereby the intermeshing gears carried by the shafts 59, 61, and 63 respectively may be free to 100 operate. These gears are denoted by the numerals 65, 66, and 67, respectively. The purpose of the gears will also hereinafter be 105 more fully described.

A pawl and ratchet mechanism of any well known construction is associated with each of the shafts 60, 62, and 64 and is arranged within the vertical cut-out portions 56 as shown generally at 68 in Figure 9. This construction will prevent the rotation 110 of the aforementioned shafts in one direction.

A pair of coacting coin receiving discs are secured on the inner opposed ends of each pair of aligned shafts, and the construction of these coin receiving members is more clearly illustrated in Figures 6, 7, and 8 of the drawings. With reference to the above figures, it will be seen that the coin receiving discs 69 and 70 have formed on their inner 120 opposed faces the curved ribs 71 and 72 respectively. These ribs are so arranged as to provide an interfitting relation when the complementary discs are in position on the inner ends of the respective pairs of aligned shafts, as shown in Figure 6.

The opposed ends of the series of ribs arranged on the inner face of each disc con-

verge gradually toward the center so as to form the coin receiving pockets 73 and 74 at the top and bottom respectively of each pair of discs. A pocket construction of the above character will prevent the accidental displacement of a coin when the latter has been discharged from its respective chute by gravity into the proper pocket 74. It is of course to be understood that the coin receiving pockets 73 and 74 formed in each pair of coating discs are of such size as to be adapted to receive a coin of a predetermined denomination.

Manifestly, the coating coin receiving discs which are secured on the inner opposed ends of the shafts 59 and 60 will have its pocket of such a size as to receive a five-cent piece. The complementary discs arranged on the inner opposed ends of the intermediate pair of aligned shafts 63 and 64 will have its coin receiving pocket of such size as to receive a ten-cent piece. The other end pair of discs which are supported on the inner opposed ends of the shafts 61 and 62 respectively, has its coin receiving pocket of such size as to be adapted to receive a twenty-five cent piece. Normally the coin receiving pocket 74 of each pair of complementary discs is disposed at the bottom and out of registry with the lower ends of the respective coin chutes heretofore mentioned.

As further illustrated in Figure 9, the coin receiving discs are disposed within the cut out portion 54, and in order to prevent interference of the complementary pairs of discs, the intermediate pair of discs are disposed out of alignment with respect to the other or end pairs of discs and consequently the central or intermediate coin chute 50 will also be disposed out of alignment with respect to the end chutes 49 and 51.

The operating mechanism for actuating the initial and secondary coin receiving means includes a vertical shaft 75. This shaft extends through the lateral extension 56 formed on the lower portion of the block 52, the upper end of the shaft extending upwardly through a U-shaped bracket 76 arranged on the front side of the frame 33. The lower end of this shaft extends through the false bottom 77 which is arranged in the lower portion of the stationary cylindrical casing 19. An angular bracket 78 is secured to the bottom of the false bottom 77, and the lower end of the shaft 75 also extends through said bracket.

A drive shaft 79 is journaled transversely through the cylindrical track 2, and the lower portion of the stationary cylindrical casing 19. The inner end of the drive shaft extends through the downwardly extending portion of the bracket 78 while the outer end of the shaft is disposed outwardly of the track section 2. Intermeshing bevel gears 80 and 81 are secured on the inner end of the

drive shaft 79 and the lower end of the driven shaft 75 respectively, as is more clearly illustrated in Figure 2.

A beveled gear 82 is secured on the intermediate portion of the vertical driven shaft 75, and the same meshes with the beveled gear 83 which is carried by the outer end of the shaft 59, the latter being journaled transversely in the block 52 adjacent one end thereof in the manner as heretofore more fully described.

An operating handle 84 is secured on the outer end of the drive shaft 79, and for the purpose of limiting the rotation of the drive shaft in either direction, there is provided on the operating handle a stop pin 85, the latter being adapted for engagement with the stop lugs 86 and 87 which are disposed on opposite sides of the shaft 79, and the same extend laterally from the member 88 which is arranged on the outer side of the circular track section 2. This construction is more clearly illustrated in Figures 3 and 4 of the drawings.

A relatively short rotatable shaft 89 is journaled transversely between the arms of the U-shaped bracket 76. A gear 90 is carried by the outer end of the said shaft, and the same meshes with the gear 46. The shaft 89 is rotated through the medium of the intermeshing bevel gears 91 and 92 carried by the upper end of the shaft 75 and the intermediate portion of the transverse shaft 89 respectively. This construction is clearly illustrated in Figures 1 and 2 of the drawings, and also is fully described in the divisional application covering the fraud preventing device. In this manner, the initial coin receiving apparatus will operate simultaneous with the secondary coin receiving means.

A series of vertically arranged shafts 93, 94 and 95 have their upper ends extending through the lateral extension 58 formed on the block 53, and the lower ends of these shafts extend through the cross bar 96. Suitable bevel gears 97, 98 and 99 are secured on the upper ends of the shafts 93, 94, and 95, respectively, and these bevel gears mesh with similar bevel gears 100, 101 and 102 which are secured on the outer ends of the shafts 60, 62, and 64 respectively, in the manner as more clearly illustrated in Figure 9. The ratio between the aforementioned intermeshing gears is 2 to 1.

Carried by the lower ends of the shafts 93, 94, and 95 are the slide plate actuating discs 103, 104, and 105, respectively. These discs are disposed in suitable openings provided therefor in a mount plate 106 which extends transversely in the lower portion of the stationary cylindrical casing 19, and is spaced slightly above the false bottom 77. The mount plate 106 is provided for the purpose of supporting the change holding

magazines 107 and 108 respectively. The forward portion, or rather the portion of the mount plate which is disposed adjacent the front or article discharge portion of the vending machine is provided with suitable openings for receiving and supporting the lower ends of these change holding magazines or tubes, the latter extending upwardly into the stationary cylindrical casing 19 to a point below the blocks 52 and 53.

Angularly disposed guide chutes 109 and 110 afford communication between the coin holding pockets of the complementary discs arranged on the inner opposed ends of the aligned shafts 59 and 60 and the coin receiving pockets of the complementary discs arranged on the inner opposed ends of the aligned shafts 63 and 64 with the upper ends of the change holding magazines or tubes 107 and 108 respectively in the manner as clearly illustrated in Figure 2.

Interposed between the false bottom 77 of the stationary cylindrical casing 19, and the mount plate 106 are the slidable ejector actuating plates 111, 112 and 113 respectively. Suitable guides 114 are secured on the upper face of the false bottom 77, and the same engage the outer edges of the outermost plates 111 and 112 respectively in the manner more clearly illustrated in Figure 5.

The forward portion of the plate 111 is cut away as indicated at 115 so as to clear the shaft 75 when the machine is in operation in the manner to be presently more fully described. The construction of this particular plate is shown in Figure 12.

As is shown more clearly in Figures 5, 11 and 12, each of the ejector actuating plates 40 is of substantially rectangular design. A transversely extending slot 116 is provided adjacent the rear end of the slidable ejector actuating plate 111, similar slots 117 and 118 being formed in the slidable actuating plates 112 and 113 respectively. The forward longitudinal edge of each slot is cut away at the intermediate portion thereof as indicated at 119, the purpose of this construction being hereinafter also more fully described.

An opening 120 is formed in the forward end portion of the intermediate slidable plate 113, and this opening is of such diameter as to be adapted to receive a five-cent piece when such a coin is disposed in a flat position. This opening 120 is further adapted for registry with the lower end of the change holding magazine 107 in which the five-cent pieces which are deposited in the vending machine are collected. An opening 121 is formed in the forward end portion of the slidable plate 112 and the same is of a diameter equivalent to the diameter of a ten-cent piece. This opening 65 is adapted for communication with the

lower end of the change holding magazine or tube 108 which also receives and collects coins of the denomination of ten cents, which coins are deposited in the vending machine. 70

The false bottom 77 is provided with similar openings 122 and 123 respectively, the same being adapted for cooperation with the openings 120 and 121 respectively. The openings 122 and 123 which are formed in the false bottom 77 are arranged forwardly of the forward ends of the slidable ejector actuating plates 113 and 112, and normally the openings 120 and 121 formed in the slidable ejector actuator plates 113 and 112 respectively are out of alignment with the openings 122 and 123 respectively. The opening 122 is enlarged, by cutting away the forward portion thereof and the purpose of this construction will be later described. 85

The means for ejecting the articles from the several compartments of the machine into the delivery chute 10 comprise an ejector block 124. This block is of a thickness equal to the thickness of the package 90 of the merchandise which is vended.

The block is supported on the laterally disposed lower end 125 of the vertically disposed plate 126 in the manner shown more clearly in Figure 10. This plate is arranged within the stationary casing 19 forwardly of the change holding magazine. The upper end of the plate is pivotally suspended from the substantially U-shaped bracket 127 which extends laterally from the block 52, through the medium of the loop member 128 which is attached to the upper end of the plate. 95

If desired, a spring finger 129 may be secured on the forward edge of the ejector block 124 for properly positioning the lowermost package in the compartment disposed adjacent the delivery chute 10. The construction of the ejector block and its support is further fully covered in the divisional application relative to the cabinet construction per se of the vending machine. 105

The lower end portion of the plate, and the ejector block carried thereby are disposed directly adjacent the forward ends of the slidable plates 111, 112 and 113. Furthermore, the ejector block 124 as well as the lateral extension 125 are adapted for slidable movement through the registering openings 21 and 22 formed in the stationary cylindrical casing 19, and the rear walls of the several compartments 5 respectively as is obvious from the construction shown more clearly in Figure 1. 115

The lower portion of the plate 126 as well as the central portion of the ejector block 124 and lateral extension 125 are cut out as indicated at 130 for cooperation with the enlarged opening 122 as will be previously set forth. 120 125 130

An upstanding pin 131 is carried by the forward end of the slidable plate 111, similar pins 132 and 133 being carried by the forward ends of the other slidable plates 112 and 113 respectively. The pin 131 is adapted for engagement with the lug 134 which extends rearwardly from the lower vertical portion of the plate 126 on one side of the cut out portion 130. A similar lug 135 is arranged on the opposite side of the cut out portion and cooperates with the closely related pins 132 and 133 in the manner as shown in Figure 5, so that the ejector block will be moved forwardly by the pins 15 in the manner hereinafter more fully described.

As is clearly illustrated in Figure 1, the inclined portion 136 of the delivery chute 10 has its inner end disposed rearwardly of the openings 122 and 123 formed in the false bottom 77 of the stationary cylindrical casing 19, the forward portion of the cylindrical casing being provided with a slot 137 through which the inclined portion 128 of the delivery chute is adapted to extend.

Depending from the bottom of each of the discs 103, 104, and 105, is the pin 138. These pins are adapted to be disposed within the slots 116, 117, and 118 respectively, as clearly illustrated in Figures 1 and 5 of the drawings, and provide a means whereby the respective slidable plates will be moved forwardly for effecting the actuation of the lower free end of the plate 126 and the ejector block 124 carried thereby.

For the purpose of normally holding the slidable plates in their rearwardmost positions, so that the ejector block is disposed behind the lowermost package in the compartment or magazine which is positioned over the delivery chute 10, I provide each of the slidable plates with a downwardly projecting pin 139. These pins extend downwardly through suitable longitudinally extending slots 140 formed in the false bottom 77 of the cylindrical stationary casing 19.

A series of coil springs 141 are secured at their rear ends to the inner face of the rear portion of the casing 19. These coil springs are secured at their forward ends to the lower ends of the respective downwardly projecting pins 139.

An elongated slot 142 is formed in the rear portion of the false bottom 77, and cooperating therewith is the lower end of the upwardly inclined coin chute 143. The upper end of this coin chute is adapted for communication with the coin receiving pocket formed in the inner opposed faces of the complementary discs 61 and 62. Slidable through the rear portion of the stationary casing 19, and adapted to be disposed beneath the slot 142 is the coin receiving box 144. The rear wall of the box is formed

by cutting away the rear portion of the base and circular tracks 1 and 2 respectively. In this manner, the coin holding box may be readily and easily removed from the machine without interfering with the mechanism provided for vending the articles.

A coil spring 145 extends between the front face of the inclined coin chute 143 and the rear face of the lower portion of the suspended plate 126 for normally holding the ejector block in its rearwardmost position, and this particular construction is clearly shown in Figure 1 of the drawings.

Forming a part of the slug handling device is the hopper 146, the same being arranged at the rear side of the block 53 of the secondary coin receiving means, and projecting upwardly from the front face of the hopper is the lip 147, the same being adapted for cooperation with the deflector plate 148 which is inclined downwardly from the rear side of the coin chute 48.

A coin chute 149 extends from the bottom of the hopper 146, and this chute is disposed toward the front of the machine so that the discharge end thereof will communicate with the cut out portion 130 formed in the lower portion of the pivotally suspended plate 126, and the ejector block 124 as well as the lateral extension 125 formed on the lower end of the respective plate, and on which the ejector plate is mounted.

The operation of my improved vending machine may be briefly stated as follows: The several magazines 5 are filled with the merchandise to be vended, and as heretofore stated, the merchandise is preferably put up in package form and may consist of candy, chewing gum, cigarettes, cigars, or the like, which articles are now marketed in packages to insure the sanitary handling thereof. After the several magazines have been filled, and the change holding magazines are also initially filled or partially filled, the cover 17 is placed on the top of the casing 4 and may be secured thereon in any suitable manner.

In the present instance, the merchandise is to be vended at the sale price of five cents per package. When a person wishes to obtain an article from the machine, one of the handles 16 is grasped and the casing 4 is rotated until the desired article which is readily visible through the glass panels 8 is disposed directly over the delivery chute 10. The rollers 18 will then be disposed in the several notches 14 formed in the upper edge of the circular track 2 to insure the proper positioning of the casing 4 with respect to the delivery chute 10, as is clearly brought out in the divisional application covering the cabinet construction.

By depositing a coin of the denomination of five cents in the slot 25, it will be readily seen that the coin will by gravity pass downwardly through the chute 29 and will be dis-

charged into the pocket provided therefor in the shaft 32. The operating handle 84 is then swung forwardly in an arc of 180 degrees, the forward swinging movement of the operating handle being limited by the pin 85 coming into engagement with the projection 87. During the forward swinging movement of the operating handle, the shaft 75 will be rotated through the medium of the drive shaft 79 by means of the intermeshing gearing heretofore described. When the operating handle 84 is being swung in a forward direction, the coil spring 150 which encircles the drive shaft 79 and is attached at one end thereto, and at its other end to the casing 19, will be placed under tension. The shaft 89 will be simultaneously rotated with the shaft 75, as will also the shaft 32 which is geared to the shaft 89. The shaft 44 will also be caused to rotate simultaneous with the rotation of the shaft 32 and as the shaft 32 rotates in the direction of the arrows, the coin will be moved into engagement with the spring pressed knurled roller 37, which is disposed adjacent the end of the shaft 32 in which the pocket is formed, and if the proper coin has been inserted in the machine, the coin will pass the roller without being bent and will fall upon the plate 43 which will be in the position as shown in full lines in Figure 13 of the drawings, thus acting as a guide for deflecting the coin into the hopper of the chute 48.

In the mean time, the shaft 59 of the secondary coin receiving means will have rotated in an arc of 180 degrees so as to position the pocket 74 into registry with the lower end of the coin chute 49 so that the coin will by gravity enter the pocket 74, and thus interlock the discs 69 and 70 which are carried on the inner opposed ends of the aligned shafts 59 and 60.

The operating handle 84 is then swung rearwardly to further effect the rotation of the driven shaft 75 as well as the rotation of the interconnected shaft 59 and 60, and through the medium of the bevel gearing 97 and 100, the shaft 93 will be simultaneously actuated. The actuation of the shaft 93 will also cause the rotation of the disc 103 secured on the lower end of the shaft and the pin 138 which projects downwardly from this disc will operate in the slot 116 formed in the rear end portion of the slidable ejector actuating plate 111 to cause the plate to move forwardly against the tension of the coil spring 141. As the plate 111 is slid forwardly over the false bottom 77, the upstanding pin 131 which is in engagement with the rear edge of the lug 134, the latter projecting from the rear face of the pivotally suspended plate 126 will force the ejector block forwardly through the registering cut out portions 21 and 22 and the spring

finger 129 which is secured on the forward edge of the ejector block will engage the lowermost package in the bottom of the container positioned over the chute 10 forwardly through the cut out portion 11, and will discharge the package into the delivery chute 10 where the same may be easily obtained by the purchaser. For the purpose of normally preventing the accidental displacement or discharging of the packages from the containers into the delivery chute, there is provided the downwardly projecting spring fingers 151 with reference more particularly to Figure 4 of the drawings. When the interlocked discs have rotated for approximately 180 degrees, the pocket 74 will then be disposed in communication with the upper end of the guide chute 109, and thereby the five cent piece will be discharged from the pocket into the chute and will be finally delivered to the five cent piece receiving magazine 107.

The lug 86 will limit the rearward swinging movement of the operating handle 84 and when the article has been discharged from its magazine into the delivery chute 10, and the coin has been automatically discharged from the pocket provided by the complementary disc carried by the inner opposed ends of the aligned shafts 59 and 60, in the magazine 107 through the medium of the guide chute 109, is a spring associated with the pin which depends from the disc 103 will automatically return the slidable plate 111 and the ejector plate will also be returned to its normal position through the medium of the spring 145. The complementary discs on the inner opposed ends of the aligned shafts 59 and 60 will be rotated so as to normally position 74 at the bottom and out of registry with the guide chutes 49 simultaneous with the reverse rotation of the shaft 75 caused by the coil spring 150 which encircles the drive shaft 79. In this manner, the discs will again be disposed in position, and thus resetting the initial as well as the secondary coin receiving mechanism.

Should a ten cent piece be deposited in the slot 26, the coin will pass downwardly through the chute 30, and will enter the pocket provided therefor in the shaft 32, and by actuating the operating handle in the manner heretofore described, the several parts which are geared together will rotate simultaneously to effect the discharge of the coin from the pocket 75 in the shaft 32 and permit the same to enter the pocket 74 which has been moved to the top, and into communication with the lower end of the guide chute 50 so that when the ten cent piece enters the pocket 74 of the complementary disc secured on the inner opposed ends of the aligned shaft 63 and 64, the discs will be interlocked and the shafts interlocked.

The operating handle is then swung rearwardly to discharge the coin from the secondary coin receiving means and to simultaneously actuate the ejector block, and the 5 last mentioned operation is accomplished by the rotation of the shaft 95 rotating the disc 105 to cause the pin carried by the disc to operate in the slot 118 and move the intermediate slidable plate 113 forwardly so 10 that the upstanding pin 133 will engage the lug 135 carried by the suspended plate 126 and move the ejector block forwardly.

The opening 120 formed in the forward end portion of the slidable plate 113 is 15 normally in registry with the lower end of the coin chute 107 and the opening is of such thickness as to receive a single five cent piece. It is obvious that as the plate 113 moves forwardly, the same will carry 20 with it a coin of a denomination of five cents, and when the opening 120 is in registry with the opening 122, the five cent piece will be automatically discharged from the slidable plate 113 into the inclined portion 25 136 of the delivery chute 10 so that the purchaser of the article will receive five cents in change simultaneous with the delivery of the article purchased.

When the interconnected or interlocked 30 shafts 63 and 64 have rotated for approximately 180 degrees, the coin receiving pocket 74 will be returned to its normal position, and will be in registry with the coin delivery chute 110, and a ten cent piece will 35 by gravity be discharged from the pocket of the complementary disc carried by the inner opposed ends of the last mentioned pair of aligned shafts into the magazine 108 which receives coins of the denomination 40 of ten cents. The discs and the slidable ejector plate actuating member will be returned to their normal positions in the same manner as heretofore more fully described.

When a twenty-five cent piece is inserted 45 into the slot 27, the same passes downwardly through the chute 31 into the coin receiving pocket, provided therefor in the shaft 32 and the initial and secondary coin receiving means is then actuated in the same manner 50 as above set forth so that the twenty-five cent piece will be deposited in the coin receiving pocket 74 formed by the complementary disc carried by the inner opposed ends of the shafts 61 and 62 respectively. 55 The handle 84 is then again actuated so that the interconnected shafts 61 and 62 will effect the rotation of the shaft 94 which in turn will cause the slidable plate 112 to move forwardly through the medium of the disc 104 and the pin 138 carried thereby cooperating with the slot 117 formed in the rear portion of the plate 112. As the plate 60 112 is slid forwardly, the upstanding pin 132 carried on the forward end portion 65 thereof and which is in engagement with the

projection 135 will force the lower portion of the pivotally suspended plate 126 forwardly so that the ejector block 124 will also move forwardly and into cooperative relation with respect to the lowermost packing in the bottom of the magazine or compartment which is disposed over or in alignment with the delivery chute 10.

The opening 121 provided in the forward end portion of the slidable plate 112 is of such thickness as to be adapted to receive two ten cent coins at a time, and normally two of such coins will be disposed within the opening by reason of the fact that this opening is normally in registry with the lower end of the change holding magazine 108. Manifestly, when the slidable plate 112 is moved forwardly, the two ten cent coins will be carried forwardly until the opening 121 is in registry with the opening 123 formed in the false bottom 77, and when this occurs, the two ten cent pieces will automatically be discharged from the slidable plate 112, and will by gravity be deposited into the delivery chute 10 simultaneously with the delivery of the package from the selected magazine or compartment 5. Thus when a person deposits twenty-five cents, he will receive a package, the cost of which is five cents, and change amounting to twenty cents.

In the present instance, no provision is made for receiving the twenty-five cent pieces which have been deposited in the vending machine so that said coins may be returned when making the desired change; depending upon the denomination of the coin which is initially inserted into the machine. It is however, to be understood that I do not wish to limit myself to the particular number of coin chutes and slots, as well as the change holding magazines, nor do I wish to limit myself to the operation of the vending mechanism by a single coin, it being understood of course that any number of coins may be made to effect the actuation of the ejector mechanism.

The twenty-five cent pieces will be deposited or collected in the coin receiving box 115 144 through the medium of the guide chute 143 which extends from the bottom of the secondary coin receiving means directly below the pocket 74 of the complementary disc arranged on the inner opposed ends of the shafts 61 and 62, the lower end of this chute communicating with the slot 142 which is of such width as to permit coins of the denomination of twenty-five cents to easily pass therethrough into the coin receiving box.

The return mechanism associated with the slidable plate 112 and the discs associated with the shafts 61 and 62 is identical with the mechanism provided for the other plate

and shaft, and as the same has heretofore been more fully described, it is not thought necessary to further go into detail relative to the same.

5 The provision of the ratchet mechanism 68 will prevent the rotation of the shafts 60, 62 and 64 when the latter are connected to their aligned shafts 59, 61 and 62 respectively in one direction so that should the operating 10 handle 84 accidentally slip out of the operator's hand when being swung rearwardly, the handle will not automatically return to its normal position and not cause the person operating the machine to lose the coin inserted by him without obtaining the desired merchandise. The train of gears 65 and 66, and 67 enables the shafts 59, 61, and 63 respectively to be operated by a single drive shaft 75 and the intermeshing bevel gearing 15 82 and 83.

As the slug handling mechanism is fully disclosed in a divisional application covering the fraud preventing device, a further discussion thereof in the present application 20 is thought unnecessary.

It will thus be seen from the foregoing description, that a coin controlled vending machine has been provided which will at all times be positive and efficient in its operation, and will not in any way necessitate the 25 services of an attendant in order to make the proper change when a purchaser desiring one of the articles from the machine does not possess the proper coin or coins necessary to operate the machine.

The simplicity in which my improved vending machine is constructed renders the same easily and readily assembled and will furthermore be inexpensive, yet strong and durable, as well as presenting a neat and attractive appearance. It will of course be understood that any advertising or other indicia may be placed on the machine as may be desired.

45 While I have shown the preferred embodiment, it is to be understood that minor changes in the size, shape and arrangement of parts may be resorted to without departing from the spirit of the invention or the 50 scope of the appended claims.

Having thus described the invention, what I claim as new is:—

1. A coin control for an ejector actuating mechanism of a vending machine comprising in combination, a plurality of pairs of spaced aligned shafts, the inner opposed ends of each pair having complementary discs carried thereby, means arranged on the inner opposed faces of each pair of discs for spacing the same from each other, said means further providing a coin receiving pocket, a coin chute associated with each pair of shafts and having its discharge end disposed above the pair of discs for cooperation with said 55 pocket, each pair of spaced aligned shafts

being adapted to be interlocked independently by the insertion of a coin in the chute, said chute causing the coin to be disposed in said pocket, means for operatively connecting one shaft of each pair of shafts together, 70 means for manually rotating the shafts when the same are interlocked, and additional means operatively connecting the shafts with the ejector actuating mechanism.

2. Means for actuating an ejector for a 75 vending machine comprising in combination, a plate, the forward end thereof being operatively associated with the ejector, a rotatable shaft disposed vertically above the rear portion of the plate and cooperative means 80 associated with said plate and the lower end of the shaft to effect the forward sliding movement of the plate when the shaft is actuated.

3. Means for actuating an ejector for a 85 vending machine comprising in combination, a plate, the forward end thereof being operatively associated with the ejector, a rotatable shaft disposed vertically above the rear portion of the plate, cooperative means 90 associated with said plate and the lower end of the shaft to effect the forward sliding movement of the plate when the shaft is actuated, and coin controlled means for actuating the shaft.

4. Means for actuating an ejector for a vending machine comprising in combination, a plate, the forward end thereof being operatively associated with the ejector, a rotatable shaft disposed vertically above the rear portion of the plate, cooperative means associated with said plate and the lower end of the shaft to effect the forward sliding movement of the plate when the shaft is actuated, said means comprising a pin carrying member secured on the lower end of the shaft, and disposed above the plate, the rear portion of said plate having a transversely extending slot formed therein, and a pin projecting downwardly from said member and 100 operable in said slot.

5. Means for actuating an ejector for a vending machine comprising in combination, a plate, the forward end thereof being operatively associated with the ejector, a rotatable shaft disposed vertically above the rear portion of the plate, cooperative means associated with said plate and the lower end of the shaft to effect the forward sliding movement of the plate when the shaft is 115 actuated, and means for returning the movable elements to their normal positions.

6. In combination, a coin control mechanism for actuating an ejector operating mechanism, a change holding magazine open at its lower end, said ejector operating mechanism including a slideable plate, the forward end thereof being operatively associated with said ejector, said plate having a coin receiving opening formed therein nor- 125 130

mally in registry with the open lower end of said change holding magazine, means for operatively connecting said plate with said coin control mechanism whereby the plate 5 will move forwardly to actuate said ejector and simultaneously discharge the change from the opening in said plate when a coin of a greater denomination than the cost of the article sold is inserted in the coin control 10 mechanism and the latter is operated.

7. In combination, a coin control mechanism, change holding magazines open at their lower ends, delivery chutes extending from the coin control mechanism to the 15 upper open ends of the change holding magazines, slide plates arranged beneath the respective magazines, means for operatively connecting said slide plates with said coin controlled mechanism, each of said plates 20 having a coin receiving pocket arranged therein normally disposed in registry with the open lower end of the respective change holding magazines, the change carried by the plates being adapted to be discharged 25 therefrom when a coin of a greater denomination than the cost of the article sold is inserted in the coin control mechanism and the latter is actuated, said plates forming a closure for the open lower ends of the magazines when the same are moved forwardly, and means for returning the slide plates 30 to their normal positions.

8. Means for actuating an ejector for a vending machine wherein the ejector is pivotally suspended at its upper end, comprising in combination, a plate, said plate being operatively associated with the ejector, and means for actuating said plate.

9. Means for actuating an ejector for a vending machine wherein the ejector is pivotally suspended at its upper end, comprising in combination, a plate, said plate being operatively associated with the ejector, coin controlled means for actuating said plate, 45 and means for returning the pivotally suspending ejector to its normal position simultaneously with the return of said plate.

10. Means for actuating an ejector for a vending machine wherein the ejector is pivotally suspended at its upper end comprising in combination, a slide plate, the forward end thereof being operatively associated with the lower end of said ejector, a rotatable shaft disposed vertically above the 55 rear portion of the plate, cooperative means associated with said plate and the lower end of the shaft to effect the forward sliding movement of the plate when the shaft is actuated, and coin controlled means for operating the shaft.

11. In combination, a coin controlled mechanism, change holding magazines open

at their lower ends, a mount plate for the magazines, a bottom forming plate disposed below the open lower ends of the magazines, an ejector actuating slide plate arranged between the open lower end of each magazine and the bottom forming plate, and operable with said coin controlled mechanism, each slide plate having a coin receiving pocket formed therein normally in registry with the open lower end of the respective magazine, said bottom forming plate being provided with openings in the forward end portion thereof, forwardly of 75 said magazines, the change deposited in said magazines being adapted to be discharged therefrom when a coin of a greater denomination than the price of the article sold is inserted in the coin controlled mechanism, 80 the change being discharged when the openings in the slide plate are in registry with the openings in the bottom forming plate, means for actuating said coin controlled mechanism, said slide plate forming closures for the open lower ends of the respective change magazines when moved forwardly, and means for returning the slide plates to their normal positions.

12. Means for actuating an ejector for a vending machine comprising in combination, a plate, the forward end thereof being operatively associated with the ejector, a rotatable shaft disposed vertically above the rear portion of the plate, cooperative means associated with said plate and the lower end of said shaft to effect the forward sliding movement of the plate when the shaft is actuated, a pin projecting from the bottom of said plate, and a retractile coil spring 100 cooperating therewith for returning the slide plate to its normal position.

13. Means for actuating an ejector for a vending machine comprising in combination, a plate, the forward end thereof being operatively associated with the ejector, a rotatable shaft disposed vertically above the rear portion of the plate, cooperative means associated with the plate at the lower end of the shaft to effect the forward sliding movement of the plate when the shaft is actuated, said means comprising a pin carrying member secured on the lower end of the shaft, and disposed above the plate, the rear portion of said plate having a transversely extending slot formed therein, a pin projecting downwardly from said member and operable in said slot, a pin projecting from said plate, and a retractile coil spring associated with the last mentioned pin for returning the slide plate to its normal position.

In testimony whereof I affix my signature.
WILLIAM F. DONATHAN.
